SINGLE-BLADE PROPELLER

Walter W. Everts, Baltimore, Md., assignor to
 Everel Propeller Corporation, Baltimore, Md.,
 a corporation of Maryland

Application November 1, 1939, Serial No. 302,423

11 Claims. (Cl. 170—164)

My invention relates to improvements in single-blade propellers.

An important object of the invention is to provide a single-blade propeller which is particularly well adapted for use upon air craft, but which is also adapted for use in connection with boats including surface ships or submarines and fans used for ventilating purposes or the like.

A further object of the invention is to provide a propeller of the above mentioned character, which is automatically actuated by the action of centrifugal force, to vary its pitch, as the pressure of the fluid medium within which the propeller is operating varies.

A further object of the invention is to provide a simplified pivotal mounting for the variable pitch propeller which will permit of the propeller automatically finding its plane of rotation.

A further object of the invention is to provide means for accurately balancing the propeller statically, vertically and horizontally.

A further object of the invention is to provide means to balance the propeller dynamically.

A further object of the invention is to provide a propeller of the above mentioned character, having its pivotal mounting enclosed and its leading side covered.

A further object of the invention is to provide means to limit the swinging movement of the propeller for varying its pitch.

Other objects and advantages of the invention will be apparent during the course of the following description.

In the accompanying drawings forming a part of this application and in which like numerals are employed to designate like parts throughout the same,

Figure 1 is a front elevation of a single-blade propeller embodying my invention,

Figure 2 is a transverse section taken on line 2—2 of Figure 1,

Figure 3 is a vertical section taken on line 3—3 of Figure 2, parts broken away,

Figure 4 is a plan view of the propeller, parts broken away,

Figure 5 is a horizontal section taken on line 5—5 of Figure 1,

Figure 6 is a vertical section taken on line 6—6 of Figure 4,

Figure 7 is a front elevation of the propeller, partly diagrammatic, with the propeller horizontal,

Figure 8 is a plan view of the same,

Figure 9 is a front elevation of the propeller, partly diagrammatic, showing the same vertical,

Figure 10 is a rear end elevation of the front cap, and,

Figure 11 is an exploded perspective view of the coupling hub and associated elements.

5 In the drawings, wherein for the purpose of illustration is shown a preferred embodiment of my invention, the numeral 10 designates a single-blade propeller as a whole. The propeller includes a single blade 10' having a center-line 10a. 10 The propeller blade 10' has a leading section 11' and a trailing section 12', which are unbalanced, the trailing section having the greater area. This propeller may be formed of any suitable material, such as aluminum, an aluminum alloy, Bakelite, wood, or the like. The propeller is preferably formed integral and comprises a hub 11, carrying a shank 12 upon one side, which carries the blade 10'. The hub has a counter-weight shank or member 13 integral therewith, arranged opposite the shank 12. The hub 11 has circularly curved portions 14, extending radially beyond the shank 12 and counter-weight shank or member 13. The action of centrifugal force upon the blade 10' and counter-weight shank or member 13, produces radial thrusts in opposite directions which are balanced. The entire propeller is also substantially statically balanced both horizontally and vertically.

The propeller hub 11 is provided with a central circular recess 15, receiving oppositely arranged bearing blocks or members 16, having flat inner faces 17 and cylindrically curved outer faces 18. Each bearing block 16 has curved end flanges 19 and flat end faces 20. Each bearing block 16 has a cylindrical recess 21. Arranged within each cylindrical recess 21 is a bearing sleeve 22, having a tapered opening 23, which is circular in cross-section, and increases in diameter inwardly. This bearing sleeve receives a bronze bushing 24, having an outer tapered wall and an inner tapered opening or bore 25, which is circular in cross-section and increases in diameter inwardly. The bronze bushing 24 is preferably apertured for the passage of a lubricant. 30 35 40 45 50 55 The bronze bushings receive preferably hollow pivot elements 26, which are exteriorly tapered to properly fit within the bronze bushings. The pivot elements are preferably formed integral with a coupling hub 27, which is tubular, to receive the crank shaft 28 of the engine of an aeroplane or the like. The pivot elements 26 are diametrically oppositely arranged with respect to the coupling hub 27 and shaft 28 and their central longitudinal axes are in a line 26'. The line 26' is radial with respect to the coupling hub

27 and disposed in a transverse plane at a right angle to the central longitudinal axis of the coupling hub 27. The line 26' is inclined or diagonal with respect to the center line 10^a. Lines 10^a and 26' intersect and both pass through the center of the coupling hub 27. The numeral 29 designates a washer or sealing ring, which fits within an annular recess or groove 30 formed in the inner face 17 and also rests against a flat shoulder or face 31, formed upon the coupling hub 27. This washer or sealing ring surrounds the bronze bushing 24 and engages the inner end of the bearing sleeve 22, and extends across the meeting faces of elements 22 and 18.

The bearing blocks 16 and associated elements are assembled upon the coupling hub 27 and these assembled parts are inserted into the circular opening 15.

A disc 32 is arranged upon the rear side of the propeller hub 11, and this disc is provided upon its inner face with an annular groove 33, to receive the flanges 19. This disc also has a center opening 34 which is slightly elliptical. Disposed upon the front side of the propeller hub 11 is a companion disc 35, provided upon its inner face with an annular groove 36, receiving the flanges 19. This disc 35 has a center opening 37 which is preferably circular. The discs 32 and 35 are connected by main bolts 38, passing through openings 39 and 40 formed in the discs 32 and 35 respectively. These bolts also pass through suitable openings formed in the propeller hub 11. The main bolts carry tapered washers 41 at their forward ends, and nuts 42, having any suitable means to lock the nuts against accidental rotation. The discs 32 and 35 are further connected by auxiliary bolts 43, passing through openings 44 and through openings in the propeller hub 11 and carrying nuts 45 at their forward ends, with any suitable means to prevent accidental unscrewing of these nuts. The several bolts are so arranged with relation to each other that the propeller remains substantially statically balanced, both horizontally and vertically, and the central longitudinal axes of the bolts 38 are in alignment with the center line 10^a of the propeller. Screws 44' pass through openings in the discs 32 and 35 and engage in screw-threaded openings 45' formed in the bearing blocks 16.

The counter-weight shank or member 13 is provided with a longitudinally extending bore 46, receiving a sleeve 47, preferably formed of metal. This sleeve is cylindrical and has its central longitudinal axis in alignment with the center line 10^a. The sleeve 46 has transverse openings 48 near its inner end to receive the main bolt 38. The sleeve 47 has its outer end portion counter-bored and provided with internal screw-threads 49, to engage with screw-threads 50, formed upon the outer enlarged end portion of a weight 51. This weight has a slot 52 at its outer end to receive a screw driver or the like for turning the same. The sleeve 47 has its outer end also exteriorly screw-threaded, as shown at 53, for engagement within a cap 54, internally screw-threaded. This cap has an opening 55 at its end for the passage of a screw driver or the like. A set screw 56 has screw-threaded engagement within a screw-threaded opening 57 formed in the cap 54 and this set screw has a reduced shank 58, which is smooth, and extends through an opening 59 in the sleeve 47. This reduced shank passes to the interior of the sleeve 47 and clamps against the weight 51 to lock the weight in the selected adjusted position. The propeller as orig-

inally made, is balanced statically both horizontally and vertically, as much as possible, but is ordinarily not in true balance and the accurate balancing of the propeller statically horizontally, is effected by the adjustment of the weight 51.

Means are also provided to accurately balance the propeller statically vertically, comprising bolts 60, held within openings 61 formed in the propeller hub 11. These bolts carry nuts 62 arranged within recesses 63. Arranged beneath the nuts 62 are removable weight washers 63'. By using a suitable number of these weight washers 63', the static balancing of the propeller vertically may be approximately effected. The bolts 60 have their central longitudinal axes in alignment with the diagonal line or axis 26'. The bolts 60 are provided at their outer ends with longitudinally extending screw-threaded openings receiving adjustable weight-screws 64, passing through caps 65, which are preferably resilient. The weight-screws 64 are turned to accurately adjust the static balancing of the propeller vertically and the resilient caps 65 hold the weight-screws against accidental movement.

The numeral 66 designates a torque weight, which is mounted upon portion 14 of the propeller hub 11. This torque weight comprises a name plate 67 and one or more lead shims 68, these elements being attached to the hub by screws 69 or the like. The action of the torque weight may be varied by increasing or reducing the number of lead shims 68. The purpose of this torque weight is to counteract the uneven action of torque on a single-blade propeller. The moment exerted by the weight of this torque weight is equal and opposite to the unbalanced aerodynamic torque moment, thereby making the propeller balanced dynamically. The weight of this torque weight is calculated by a theoretical formula. The propeller assembly is balanced statically on a balance block with the propeller in both a horizontal and vertical position. When the balancing about these axes is completed, the torque weight is mounted at the intersection of the two planes; one passing through the hub axis in a vertical plane and another plane perpendicular to it passing through the longitudinal blade axis 10^a. The torque weight then throws the propeller out of static balance vertically after balance static considerations are finished, and then balances the propeller when in motion.

The crank shaft 28 has its forward end tapered and inserted within the tapered bore of the coupling hub 27, and the crank shaft has a reduced screw-threaded portion 70, which receives thereon the rear end of a tubular shaft extension 71, which rear end is internally threaded, as shown. The tubular shaft extension 71 is provided at its rear end with an exterior flange 72, to engage with a lock nut 73, engaging within a screw-threaded counter-bore 74, formed in the coupling hub 27. This lock nut prevents the accidental turning of the tubular shaft extension 71. The lock nut is held against accidental unscrewing by a cotter pin 75 or the like.

Arranged upon the front disc 35 is a cap 76, having a flange 77, secured to the bearing blocks 16 by screws 78 engaging within openings 79 formed in the block 16. The screws 78 have the further function of properly locating the cap 76 upon the disc 35 so that the recesses 80 will receive the screws 44'. Additional bolts 81 are also employed to secure the cap to the disc 35. The opening 79 leads into the bearing recess 21, so that grease or other lubricant may be fed into

the recess by a grease gun or the like, and the parts 22, 24, and 26 retained suitably lubricated.

The cap 76 has an annular chamber for receiving and holding an annular bumper 82, formed of rubber. This annular bumper is adapted to engage the tubular shaft extension 76 and serves to limit the swinging movement of the propeller upon its diagonal axis 26'. As stated, the opening 34 is elliptical and the longitudinal axis of the ellipse is at a right angle to the diagonal line or axis 26'.

Operation

The operation of the propeller is as follows:

The propeller is driven counter-clockwise, viewed from the front of the aeroplane, which is the practice in the United States. As soon as the propeller rotates, centrifugal force acts upon the propeller and tends to move it to a radial position. This action of centrifugal force is opposed by the air thrust, which tends to swing the propeller forwardly so that the outer end of the blade 10' moves forwardly from the radial position and inwardly of the maximum sweep. These two opposing forces act against each other and the blade will assume a normal operating position between the extreme forward position and the true radial position. When the blade is in the extreme forward position it is at the minimum pitch and when in the true radial position it has the maximum pitch, due to centrifugal force. Assuming that the aeroplane is now flying at substantially sea level, the air thrust is then at the maximum and the blade has moved forwardly about the surface of a cone, to assume the forwardmost position which will impart to the blade the minimum pitch. During this action of the blade, the center line 10^a of the blade travels about the surface of a cone, and the center of the cone is the line 26'. The action of centrifugal force tends to move the blade rearwardly about the surface of the cone toward the true radial position, thereby increasing the pitch of the blade. As the speed of the aeroplane increases, the air pressure acting upon the forward face of the blade tends to move the blade rearwardly about the surface of a cone for increasing the pitch of the blade. Assuming that the propeller is being flown in level flight at 2,000 R. P. M., at sea level, the propeller will then have the minimum pitch, with respect to the pitches which it will have at increased elevations. As the aeroplane now rises to a considerably higher elevation, the air thrust acting upon the propeller will be reduced, while the action of centrifugal force remains the same and hence the action of centrifugal force will overcome the air thrust upon the propeller blade, and the blade would be moved rearwardly about the surface of the cone, and thereby increasing the pitch of the propeller blade. This increased pitch of the propeller blade will cause the propeller to drive the aeroplane at an increased speed but the speed of rotation of the propeller will remain substantially constant.

When the air pressure upon the front face of the blade 10' is sufficient to overcome the action of centrifugal force, as when the aeroplane is making a nose dive, the blade 10' is shifted rearwardly beyond the radial position, and the pitch of the blade is increased over the maximum pitch which can be imparted to it due to the action of centrifugal force, which would occur when the blade is shifted by centrifugal force into a true radial position.

The blade 10' is capable of being shifted about the surface of the cone, as described within limits, to vary its pitch, and this shifting movement is limited by the tubular shaft extension 76 engaging the annular bumper 82.

It is to be understood that the form of my invention herewith shown and described is to be taken as a preferred example of the same and that various changes in the shape, size, and arrangement of parts may be resorted to without departing from the spirit of my invention or the scope of the subjoined claims.

Having thus described my invention, what I claim is:

1. In a propeller, a rotary driving element having pivot elements arranged radially thereof, said pivot elements having a common longitudinal axis, a single-blade propeller including a hub carrying a blade and counter-weight member, the blade and counter-weight member being oppositely arranged and having a common center line which passes through the center of the rotary driving element, said hub having an opening to receive the rotary driving element and its pivot elements, bearing devices arranged within the opening of the hub and secured to the hub and receiving the pivot elements, the common longitudinal axis of the pivot elements being arranged perpendicularly to and intersecting the axis of rotation of the driving element and diagonally with respect to the center line of the blade, so that the blade turns upon the pivot elements and the center line of the blade travels about the surface of a cone having the common longitudinal axis of the pivot elements as the center of the cone.
2. In a propeller, a rotary driving element having oppositely arranged radial pivot elements having a common longitudinal axis, a single-blade propeller including a hub carrying an oppositely arranged blade and counter-weight member, said hub having an opening to receive the rotary driving element and its pivot elements, bearing devices arranged within the opening of the hub for receiving the pivot elements, the common longitudinal axis of the pivot elements being arranged perpendicularly to and intersecting the axis of rotation of the driving element and diagonally with respect to the longitudinal axis of the blade, so that the blade turns about the pivot elements and its center line travels about the surface of a cone, discs arranged upon opposite sides of the propeller hub, means for securing the discs to the propeller hub, and means for securing the discs to the bearing devices.
3. In a propeller, a rotary driving element having oppositely arranged radial pivot elements, a single-blade propeller including a hub carrying oppositely arranged blade and counterweight member, said hub having an opening to receive the rotary driving element and its pivot elements, bearing devices arranged within the opening of the hub for receiving the pivot elements, the turning axes of the pivot elements being arranged diagonally with respect to the longitudinal axis of the blade, so that the blade turns about the pivot elements and its longitudinal axis travels about the surface of a cone, discs arranged upon opposite sides of the hub, means to secure the discs to the hub and to the bearing devices, a cap secured to the leading disc, said driving element having a part extending into the cap and a rubber bumper mounted within the cap to engage with said extending part of the rotary driving

element to limit the movement of the blade for changing its pitch.

4. In a propeller, the combination of a propeller shaft, a tubular coupling hub to receive a portion of the propeller shaft, said coupling hub having oppositely arranged radial pivot elements, a single-blade propeller including a hub having an opening and a blade and a counter-weight member disposed upon opposite sides of the opening, the opening receiving the coupling hub and pivot elements, bearing devices arranged within the opening of the propeller hub to receive the pivot elements, the turning axes of the pivot elements being arranged diagonally with respect to the longitudinal axis of the blade, discs arranged upon opposite sides of the propeller hub, means for securing the discs to the propeller hub and to the bearing devices, a cap secured to the leading disc, a rubber bumper held within the cap, a tubular shaft extension adapted to have screw-threaded engagement with the end of the propeller shaft and engaging the coupling hub, the tubular shaft extension being arranged to engage the rubber bumper, and a lock nut having screw-threaded engagement with the coupling hub and engaging the tubular shaft extension.

5. In a propeller, a coupling hub having oppositely arranged pivot elements rigidly secured thereto, a single-blade propeller having a hub provided with an opening and opposed blade and counter-weight members arranged upon opposite sides of the opening, bearing blocks arranged within the opening and fixedly secured to the hub, said bearing blocks having recesses, bearing sleeves within the recesses, tubular bushings within the bearing sleeves and receiving the pivot elements, sealing rings arranged between the free ends of the bearing sleeves and the coupling hub, the pivot elements having their turning axes arranged perpendicularly to and intersecting the axis of rotation of the driving element and diagonally with relation to the longitudinal axis of the blade.

6. In a propeller, a rotary driving element, a single-blade propeller including opposed blade and counter-weight members arranged upon opposite sides of the axis of rotation of the rotary driving element, pivot means fixed upon the rotary driving element and serving to connect the propeller with the rotary driving element, the fixed pivot means having its turning axis arranged diagonally with respect to the longitudinal axis of the blade, the counter-weight member having a longitudinal bore, the center line of the bore being in alignment with the center line of the counter-weight member, a sleeve held within the bore, a weight arranged within the sleeve and having screw-threaded engagement therewith, and means to lock the weight in the adjusted position.

7. In a propeller, a rotary driving element, a single-blade propeller including a hub having an opening and opposed blade and counter-weight members, pivot means fixed upon the rotary driving element, bearing devices arranged within the opening and receiving the pivot means, the pivot means having its turning axis arranged diagonally with relation to the longitudinal axis of the blade, discs arranged upon opposite sides of the hub, transverse bolts connecting the discs and securing them to the hub, means to attach

the discs to the bearing devices, said counter-weight member having a longitudinal bore, a sleeve within the bore having transverse openings receiving one of the bolts, the sleeve extending radially beyond the counter-weight member and having its outer end internally and externally threaded, a weight mounted within the sleeve and screw-threaded to engage with the internal threads of the sleeve, a cap having screw-threads to engage with the exterior threads of the sleeve, and means to lock the weight and cap against accidental unscrewing.

8. In a propeller, a rotary driving element, a single-blade propeller including opposed blade and counter-weight members arranged upon opposite sides of the axis of rotation of the rotary driving element, fixed pivot means serving to connect the propeller with the rotary driving element and having its turning axis arranged diagonally with respect to the longitudinal axis of the blade so that the blade moves about the surface of a cone, adjustable means to accurately balance the propeller statically horizontally, and adjustable means to accurately balance the propeller statically vertically.

9. In a propeller, a rotary driving element, a single-blade propeller including opposed blade and counter-weight members arranged upon opposite sides of the axis of rotation of the rotary driving element, fixed pivot means serving to connect the propeller with the rotary driving element and having its turning axis arranged diagonally with respect to the longitudinal axis of the blade, a device to accurately balance the propeller statically horizontally and adjustable along the longitudinal axis of the counter-weight member, a device to accurately balance the propeller statically vertically and adjustable along the line which is diagonal with respect to the longitudinal axis of the counter-weight member, and a device to balance the propeller dynamically and including one or more weight plates arranged between the first named devices and detachably secured to the propeller.

10. A propeller construction comprising a propeller hub having an axial opening, a rotary driving element having a part extending through the opening, means for pivotally mounting said hub on said driving element for pivotal movement about an axis transverse to the axis of the driving element, a cap mounted on said hub and surrounding the part of the driving element extending through the hub, and a bumper carried by said cap for engaging the part of the driving element surrounded by said cap to limit pivoting movement of the hub on said driving element.

11. In a propeller, a rotary driving element, a single-blade propeller including opposed blade and counter-weight members arranged upon opposite sides of the axis of rotation of the rotary driving element, pivot means fixed upon the rotary driving element and serving to connect the propeller with the rotary driving element, the fixed pivot means having its turning axis arranged diagonally with respect to the longitudinal axis of the blade, the counter-weight member having a longitudinal bore, the center line of the bore being in alignment with the center line of the counter-weight member, and a weight axially adjustably mounted in said bore.

WALTER W. EVERETT.
